UNITED STATES PATENT OFFICE.

JULIUS H. BECKER, OF SAN FRANCISCO, CALIFORNIA, ASSIGNOR TO AMERICAN HEAT & POWER CO., OF SAN FRANCISCO, CALIFORNIA, A CORPORATION OF CALIFORNIA.

AUTOMATIC CUT-OFF MECHANISM FOR OIL-BURNERS.

1,107,748.

Specification of Letters Patent. Patented Aug. 18, 1914.

Application filed March 28, 1913. Serial No. 757,281.

To all whom it may concern:

Be it known that I, JULIUS H. BECKER, a citizen of the United States, residing at San Francisco, in the county of San Francisco and State of California, have invented new and useful Improvements in Automatic Cut-Off Mechanism for Oil-Burners, of which the following is a specification.

This invention relates to an automatic 10 cut-off mechanism for oil burners.

In operating oil burners, and particularly oil burners of the down-draft type shown in the accompanying drawings, it sometimes happens that the fire becomes extinguished; 15 this being generally caused by an oversupply of water, or a corresponding reduction in the oil supply. Under such circumstances, it can readily be seen that means must be provided for automatically cutting- 20 off the fuel supply to the burner, as it would only be a matter of time when the oil injected would flood the furnace and overflow into the surrounding quarters.

The object of this invention is to provide 25 means for automatically cutting-off the fuel supply to the burners the moment the fire in the furnace becomes extinguished.

The invention consists of the parts and the construction and combination of parts 30 as hereinafter more fully described and claimed, having reference to the accompanying drawings, in which—

Figure 1 is a plan view of the furnace, partly broken away, showing the application 35 of the invention. Fig. 2 is a side elevation of same, partly broken away.

Referring to the drawings: A indicates in general a furnace of the down-draft type, having a combustion chamber 2, in which is 40 centrally mounted a burner plate 3, to which oil and water in the right proportion to support combustion is delivered from a burner 4, through a central opening 5. The burner here shown may be constructed in 45 any suitable manner, and provided with regulating valves 6 and 7 for the purpose of controlling the fuel supply in the usual manner.

Interposed on the pipe line, between the 50 regulating valves and the source of fuel supply, is a pair of cut-off valves 8 and 9, one for each line, which are here shown as being connected through links 8' and 9' with a lever 10 pivoted upon a pin 10', the movements of which will thus be simultaneously

transmitted to either open or close the valves. One end of the lever 10 is provided with an adjustable counterweight 11, having sufficient weight to normally hold the valves 8 and 9 in an open position to admit 60 the flow of fuel through the pipe lines.

Suitably mounted upon the opposite end of the lever 10 is a receptacle or overflow tank 12 to which any unconsumed oil which might have a tendency to flood the furnace 65 will be conveyed through a spout 13. The drip-pan or base portion 14 of the furnace is provided with side and end flanges of sufficient height to trap any unconsumed oil 70 discharging from the burner plate, which is thus collected and discharged through the spout to the overflow tank 12.

In operation, supposing that for some reason or other the fire within the furnace has become extinguished. It can readily be seen 75 that the oil injected through the burner will gradually cool the furnace and flood the bottom of same. The flooding oil thus discharged from the burner will in this instance be trapped by the side and end flanges 80 14, formed in the base of the furnace, and will thus be conveyed through the discharge pipes 13 to the overflow tank 12, supported upon the outer end of the pivoted lever 10. The gradual filling of the tank will soon 85 overbalance the weight 11 and rock the lever 10 into position where the fuel supply valves 90 8 and 9 will be entirely closed, thus shutting off the fuel supply to the burner and preventing any further flooding of the furnace.

For the purpose of insuring the proper closing of the oil valve at all times a slot 15 has been provided which will permit the lever 10 to swing on the water valve 9 connection, if this should happen to stick; the valve 8 can thus be closed independent of the valve 9, and the proper closing of the oil valve is thus insured at any time regardless of the valve 9.

An automatic shut-off mechanism, constructed as here shown, is simple in construction, positive and automatic in action, and may be installed in connection with any furnace using an oil burning system. The materials and finish of the different parts of the mechanism are such as experience and judgment of the manufacturer may dictate.

I wish it understood that various changes 110 in form, proportions and construction may

be resorted to within the scope of the appended claims, and that I do not wish to limit myself to the specific design and construction here shown.

Having thus described my invention, what I claim and desire to secure by Letters Patent is:

1. The combination with a furnace, of an oil burner having a fuel supply pipe and a water supply pipe connected therewith, a catch basin formed in the furnace chamber for collecting any unconsumed oil or water delivered through the burner, a lever pivotally mounted with relation to the furnace and the oil and water supply pipes, valves on said pipes, links on the lever on opposite sides of the pivot point connected with the valves, an adjustable weight on one end of the lever adapted to normally hold the lever in the depressed position when the valves will remain open, a collecting chamber on the opposite end of the lever, and means connected with the furnace catch basin for conveying the collected overflow oil or water to the collecting chamber to counterbalance the weight and rock the lever into the opposite position to close the valves.

2. The combination with a furnace having a catch basin formed in the furnace chamber of an oil burner having a fuel supply pipe and a water supply pipe connected therewith, valves on the respective pipes to control the flow of water and oil through same, a slotted lever, a pivot pin projecting through the slot, links connecting the valves with the lever on opposite sides of the slot and pivot pin, an adjustable weight on one end of the lever adapted to normally hold the lever in the depressed position when the valves will remain open, a collecting chamber on the opposite end of the lever, and means connected with the furnace catch basin for conveying the collected overflow oil or water to the collecting chamber to counterbalance the weight and rock the lever into the opposite position to close the valves.

In testimony whereof I have hereunto set my hand in the presence of two subscribing witnesses.

JULIUS H. BECKER.
